(57) **CLAIM**

The ornamental design for a holding pad for substrate transfer, as shown and described.

DESCRIPTION

FIG. 1 is an isometric view of a holding pad for substrate transfer showing our new design item.

FIG. 2 is a top plan view thereof.

FIG. 3 is a bottom plan view thereof.

FIG. 4 is a first side elevational view thereof.

FIG. 5 is a second side elevational view thereof.

FIG. 6 is a third side elevational view thereof.

FIG. 7 is a fourth side elevational view thereof.

FIG. 8 is a cross sectional view thereof taken along cut lines 8-8 of FIG. 2; and,

FIG. 9 is a bottom isometric view thereof.

The dashed lines in the drawings depict portions of the holding pad for substrate transfer that form no part of the claimed design.

The long dash-short dash-short dash lines in the drawings depict the boundaries of the claim and form no part thereof.
